(57) **CLAIM**

We claim the ornamental design for an automobile hood, as shown and described.

DESCRIPTION

FIG. 1 is a front view of an automobile hood;

FIG. 2 is a rear view thereof;

FIG. 3 is a left view thereof;

FIG. 4 is a right view thereof;

FIG. 5 is a top view thereof;

FIG. 6 is a bottom view thereof; and,

FIG. 7 is a perspective view thereof.

Broken lines in the figures show portions of the automobile hood that form no part of the claimed design.
